UNITED STATES PATENT OFFICE.

LISLE T. SCOTT, OF DETROIT, MICHIGAN, ASSIGNOR OF ONE-HALF TO THE TRAUB JEWELRY MANUFACTURING COMPANY, OF DETROIT, MICHIGAN.

EYEGLASS-CHAIN REEL.

992,269.

Specification of Letters Patent. Patented May 16, 1911.

Application filed January 20, 1911. Serial No. 603,649.

To all whom it may concern:

Be it known that I, LISLE T. SCOTT, a citizen of the United States, residing at Detroit, in the county of Wayne and State of Michigan, have invented new and useful Improvements in Eyeglass-Chain Reels, of which the following is a specification.

My invention relates to improvements in eyeglass-chain reels, and the objects of my invention are, first to produce a durable eyeglass-chain reel of small dimensions with reliable means for locking and releasing the reel to meet the demand of users who call for an article of this kind that is neat and not prominent, and second, to produce a reversible article of the kind that is adapted to be used as either right or left hand according to the convenience or preference of the user. I attain these objects by the mechanism illustrated in the accompanying drawings, in which—

Figure 1 is a face view of my complete device. Fig. 2 is a back view of the same. Fig. 3 is a rim view of the same. Fig. 4 is a section on line $x-x$ of Figs. 1 and 2. Fig. 5 is a section on line $y-y$ of Fig. 3. Fig. 6 is a section diametrically through back casing. Fig. 7 is a section diametrically through winding reel. Fig. 8 is a section diametrically through front casing, and Fig. 9 is a plan view of the locking and releasing parts.

Similar numerals refer to similar parts throughout the several views.

The scale of the drawings, Figs. 1, 2 and 3, are actual size, and in the interest of clearness Figs. 4, 5, 6, 7, 8 and 9 are drawn on an enlarged scale.

With reference to the drawings 3 is the back casing plate with the pivot 5 rigidly secured at its center; pivot 5 is slotted diametrically a part of its length, as at 6, forming segments 5', the reverse points of which are cut away at an angle 21, which forms a release 21' in the direction shown by an arrow, and a locking shoulder 23 in the opposite direction, as in action with the bolt 13. (See Fig. 9).

2 is the winding reel and comprises the chain seat 9, and a fastener 12. The spring seat 10, and fastener 11, the lock bolt seats 22 and 22' and journal 8 are adapted to be revolvably mounted on pivot 5.

1 is a hood, comprising the front and

rim, having the slot 4 cut through and at its open edge an annular groove 19 and projections 24 and adapted to be mounted securely on back casing 3. The bolt seats 22 and 22' are drilled diametrically through the winding reel from the chain seat into the journal 8, and of a diameter greater than the diameter of the sliding bolt locks 13 and 13' which are of a greater diameter than the width of the slot 6, which prevents them from dropping inwardly beyond the bevels 21. The stop plugs 14 limit the outward movement of the same. The spring 15, which may be a small size watch main spring, is fastened at one end by a hook or pin 11 while its other end engages the hook or pin 7 on the pivot 5.

The chain 18 is fastened at its inner end by the staple 12 and wound around and into its seat 9, the winding reel is then mounted on the pivot 5 with the spring 15 toward the plate 3, the reel is then turned until a slot 75 in the inner end of the spring engages the hook or pin 7 on the pivot 5, the spring is then wound by turning the plate to the right until the chain is in the position, as shown in Fig. 5, and locked. While being held in the locked position the casing 1 is placed over the reel and the plate 3 enters the groove 19, the projections 24 are then bent over its edge, which completes the assembling. The ring 25 in the end link of the chain 18 provides a stop to its inner movement.

The means to secure the eyeglass-chain reel to the garment of the user, as shown, is a hinge pin 26 and a hook 27 secured to the back casing plate 3.

Having thus described my invention I claim—

In an eyeglass-chain reel, the combination with a separable casing comprising a base plate and a hood having a slotted opening 95 and adapted to be rigidly joined together, of a pivot rigidly secured to and centrally in the plate, pockets diametrically opposite in the periphery of the pivot, one side of each pocket being beveled to form a stop in one 100 direction and a release in the opposite direction; a winding reel revolvably mounted on the pivot and having diametrically disposed bolt sockets, slideable bolts within the sockets adapted to engage the pockets, an annular 105 chain seat in the periphery of the reel, a

chain secured at one end and wound into the seat with its free end through the slotted opening and terminating with a stop ring outside the casing, a spring seat chambered in the reel, a spring mounted therein and secured at one end to the reel and at its other end to the pivot, and adapted to be wound by unwinding the chain and to re-

wind the chain by its force in unwinding, substantially as set forth.

In witness whereof I have hereunto set my hand this 18th day of January, 1911.

LISLE T. SCOTT.

In presence of—
R. H. VOLLMAYER,
F. A. ZAHNLE.
